STARTING MECHANISM FOR INTERNAL-COMBUSTION ENGINES.

1,291,805.

Specification of Letters Patent.

Patented Jan. 21, 1919.

Application filed February 9, 1918. Serial No. 216,240.

To all whom it may concern:

Be it known that I, FREDERIC EDHOLM, a citizen of the Kingdom of Sweden, residing at Eskilstuna, Sweden, have invented new 5 and useful Improved Starting Mechanism for Internal-Combustion Engines, of which the following is a specification.

This invention relates to internal combustion engines of the kind which are started 10 and reversed by means of compressed gas or air the supply of which is controlled by valves actuated by cam operated levers. The object of the invention is to provide 15 an improved starting device for engines of the said kind which is simple in construction and efficient in use.

To this end the invention consists of the novel devices and combinations of devices hereinafter described, and defined in the 20 claims.

In the drawings, which illustrate several embodiments of the invention, Figure 1 is an elevation, partly in section, of a device embodying the invention, showing those 25 parts only which are necessary for the understanding of the invention. Fig. 1^a is an end view of the control lever. Fig. 2 is an end view of the device with the shafts in cross-section. Fig. 2^a is a corresponding elevation of the control-lever. In Figs. 1-2^a the different parts are shown in their neutral position. Figs. 3, 3^a, 4, 4^a show views corresponding to Figs. 1, 1^a, 2, 2^a of the device adjusted for starting the engine in the 30 forward direction. Figs. 5, 5^a, 6, 6^a are similar views of the device adjusted for starting the engine in the reversed direction. Figs. 7 and 8 are longitudinal section and cross-section, respectively, of part of a 35 device according to another embodiment of the invention. Figs. 9 and 10 are similar sections of parts of a third embodiment of the invention. Fig. 11 is a total diagrammatic view of a plurality of cylinders of one 40 and the same engine with their starting devices.

Referring to Figs. 1 to 6^a 1 indicates the starting valve of an internal combustion engine adapted to be started by compressed gas 45 or air, and 2 is the compressed gas or air supply controlled by the valve 1. Rigidly attached to a shaft 3 which is driven by the engine in any convenient manner, is an actuating device comprising a cam disk 4 having two cams 5 and 6, corresponding to

the forward and reversed direction of movement of the engine, respectively. A shaft 7 parallel to the shaft 3 supports an eccentric 8 which in turn supports the hub 9 of a double lever 10, 11 one arm 10 of which 60 carries an antifriction roller 12 adapted to be engaged by the cam 5 or 6, as the case may be, while the other arm 11 of the lever is adapted to operate the stem of the valve 1.

The shaft 7 is both slidably and rotatably 65 mounted in suitable bearings, the movements of the shaft 7 being effected by means of a hand lever 13 rigidly attached to the shaft, and engaging a guide-way 14 formed in the stationary frame of the engine. Said guide-way 70 consists of a Z-shaped slot having a central portion extending in the longitudinal direction of the shaft 7, and two end portions at right angles thereto.

In order to enable the lever 10, 11 moving 75 axially with the shaft 7 to be moved into operative position with respect to the stem of the valve 1 irrespective of the longitudinal displacement of the shaft, the valve stem is provided with a head 15 extending 80 parallel to the shaft 7. It is obvious, that such a head may, if desired, be provided on the lever arm 11 instead of on the valve stem.

The device above described operates as follows: While the engine is at rest or is 85 running at normal speed, the lever 13 is in its neutral position, as shown in Figs. 1, 1^a and 2^a, in which the roller 12 is in a position just between the cams 5 and 6. When it is desired to start the engine in the forward direction of movement, the lever 13 is moved to the right from the position shown in Fig. 1 bringing with it the shaft 7. At the end of this movement the roller 12 is just opposite the cam 5. The roller 12 90 will, however, during this movement be out of reach of said cam, so that the latter cannot prevent the longitudinal displacement of the shaft 7. The lever 13 is thereupon turned into the position shown in Figs. 3^a 95 and 4^a. By this turning movement of the lever 13 and, consequently, also of the shaft 7, the eccentric 8 is moved from the position shown in Fig. 2 to the position shown in Fig. 4, thereby moving the lever 10, 11 100 laterally to the position shown in Fig. 4 in which the roller 12 is in reach of the cam 5, and the lever arm 11 bears against the head 15 of the valve stem. If in this movement, the cam 5 is right behind the roller 110

12, so that the latter immediately engages with the cam, the lever 11 will due to the continued movement of the eccentric 8 be swung inwardly to open the valve 1 so that 5 compressed gas or air will be admitted to the engine to start the latter immediately. If the cam 5 is in another position, the crank shaft of the engine is to be turned until the cam 5 engages the roller 12 thereby causing the 10 lever 10, 11 to open the valve 1. After starting the lever 13 is brought back to the position shown in Figs. 1, 1^a.

If it is desired to start the engine in the reversed direction of movement, the lever 15 13 is moved to the left hand end of the slot 14 and then turned to the position shown in Figs. 5^a, 6^a. The longitudinal displacement of the shaft 7 moves the roller 12 to the left to a position in front of the cam 6, 20 and by the turning movement of the shaft 7 the roller 12 is moved into the path of the said cam 6. In the same way as described above in connection with the starting for running in the forward direction of movement, the valve 1 may be opened immediately or after a more or less turning of the crank shaft of the engine. After the starting, the lever 13 is brought back to the neutral position shown in Figs. 1 and 1^a.

30 The device described may be modified in several ways without departing from the principle of the invention. For instance, the lever 13 may be turned in the same direction for starting in either direction. The 35 Z-shaped guiding slot will in such a case be substituted by a U-shaped slot.

Instead of the double movement of the lever 13 one movement only of said lever may be used for each starting operation. 40 Figs. 7, 8 and 9, 10 show two different arrangements of means for obtaining this object. The cams 5, 6, the lever 10, 11 and the valve 1 may be arranged in the same way as described with reference to Figs. 45 1 to 6.

With reference to Figs. 7 and 8, the shaft 7 is provided with a screw-thread 16 having a great angle of inclination engaging in a correspondingly threaded opening formed in 50 the frame of the engine. The lever 13 is fork-shaped and pivotally mounted on a journal 17 so as to move in a plane parallel to the shaft 7. The latter carries a pivotally mounted ring 70, which is embraced by the 55 limbs of the fork and provided with pins 71, engaging longitudinal slots formed in the said limbs, one of said pins being shown in Fig. 7. A guiding arc 18 is provided for the lever 13, and in this arc a central notch 60 19 is formed adapted to be engaged by a spring operated pin 130 slidably mounted in the latter to maintain the lever 13 with a gentle pressure in its central or neutral position in which the starting mechanism is 65 out of action. By moving the lever 13 along

the arc 18 in the one direction or the other the shaft 7 will at the same time be moved longitudinally and be turned about its own axis.

With reference to Figs. 9 and 10, the double movement of the latter is obtained by forming the shaft 7 with a lateral projection having a spherical head 20 engaging a slot or opening 21 in the lever 13. The latter is mounted on a journal 22 to move in a plane 75 parallel to the shaft 7, a guiding arc 18 being provided for the lever. In Fig. 9, I indicates the position of the head 21 in the central positions of the lever while II and III indicate the positions of said head in the end 80 positions of the lever 13. As will be readily understood, the angular movement of the shaft 7 will in this case be rather small. Hence it is necessary to choose the degree of eccentricity of the eccentric 8 correspondingly greater in order to insure sufficient movement of the lever 10, 11.

In multi-cylinder engines one set of cams 5 and 6 as well as one lever 10, 11 is used for the starting valve of each cylinder. All of 90 the cam disks 4 are attached to a common shaft 3, and all of the levers 10, 11 are mounted on a common shaft 7, as shown in Fig. 11. In multi-cylinder engines it always happens that the cam 5 or 6, as the case 95 may be, of one cylinder at least will be right opposite the corresponding roller 12 so as to be engaged by the same at the angular movement of the shaft 7 thereby effecting the opening of the corresponding 100 starting valve 1. The engine will thus always be started immediately upon the angular movement of the shaft 7.

The devices above described may not only be used for starting purposes but may also 105 be used in connection with two-stroke and four-stroke engines for controlling the inlet- and working valves for forward and reversed movement of the engine.

What I claim, and desire to secure by Letters Patent, is:

1. The combination with the starting valve of an internal combustion engine adapted to be started by means of compressed gas, of a cam disk, a slidably and 115 rotatably mounted shaft, a lever mounted on said shaft for operating the starting valve under the control of the cam disk, said lever being adapted to be moved into operative position by axial displacement and turning of said shaft.

2. The combination with the starting valve of an internal combustion engine adapted to be started by means of compressed gas, of a cam disk, a slidably and 125 rotatably mounted shaft, an eccentric attached to said shaft, a lever mounted on said eccentric to operate the starting valve under the control of the cam disk, said lever being adapted to be moved into operative 130

position by axial displacement and turning of said shaft.

3. The combination with the starting valve of an internal combustion engine adapted to be started by means of compressed gas, of a cam disk having two cams, adapted to work for forward and reversed direction of movement of the engine, respectively, a slidably and rotatably mounted shaft, an eccentric on said shaft, a lever mounted on said eccentric for operating the starting valve under the control of the cams of the cam disk, said lever being adapted to be moved into operative position with respect to the desired cam by displacing the shaft in a certain direction and then turning the same.

4. The combination with the starting valve of an internal combustion engine adapted to be started by means of compressed gas, of a cam disk, a slidably and rotatably mounted shaft, an eccentric on said shaft, a lever mounted on said eccentric for operating the starting valve under the control of the cam disk, an antifriction roller mounted on said lever for engaging with the cam disk, said lever being adapted to be moved into operative position by axial displacement and turning of said shaft.

5. The combination with the starting valve of an internal combustion engine adapted to be started by means of compressed gas, of a cam disk, having two cams adapted to work for forward and reversed direction of movement of the engine, respectively, a slidably and rotatably mounted shaft, an eccentric on said shaft, a lever mounted on said eccentric for operating the starting valve under the control of the cams, said lever being adapted to be moved into operative position by axial displacement and turning of the said shaft, a valve stem, a projection on said valve stem extending parallel with the said shaft, said projection being adapted to be acted upon by the said lever irrespective of the longitudinal displacement of the said shaft.

6. The combination with the starting valve of an internal combustion engine adapted to be started by compressed gas, of a cam disk, a slidably and rotatably mounted shaft, an eccentric on said shaft, a lever mounted on said eccentric for operating the valve under the control of said cam disk, a hand lever attached to the said shaft for operating the same, a stationary guiding slot for said hand lever to permit the

successive movement thereof in two directions at right angles to each other.

7. The combination with the starting valves of an internal combustion engine having a plurality of cylinders and adapted to be started by means of compressed gas, of a cam disk for each of the cylinders, a slidably and rotatably mounted shaft, a plurality of eccentrics on said shaft corresponding in number to the cylinders, a lever mounted on each eccentric for operating the corresponding valve under the control of the corresponding cam disks, all of said levers being adapted to be moved into operative position by the displacement and turning of the said shaft.

8. In a starting mechanism for combustion engines, the combination with a starting valve, of an actuating device, a valve operating device, and means for moving the latter axially and laterally to bring it into operative relation with the actuating device.

9. In a starting mechanism for combustion engines, the combination with a starting valve, of a valve operating lever, means for actuating the lever, and means to move the latter axially and laterally into and out of operative relation with the actuating means.

10. In a starting mechanism for combustion engines, the combination with a starting valve, of a cam disk, a valve operating lever, a rotatable and axially movable shaft carrying the latter, and means operated by the rotation of the shaft for moving the lever into operative relation to the cam disk.

11. In a starting mechanism for combustion engines, the combination with a starting valve, of a cam disk, a valve operating lever, a rotatable and axially movable shaft carrying the latter, means operated by the rotation of the shaft for moving the lever into operative relation to the cam disk, and means on the lever to maintain it in operative relation to the valve during the axial movement of the shaft.

12. In a starting mechanism for combustion engines, the combination with a starting valve, of a rotatable cam disk, a valve operating lever, a shaft carrying the latter, means to rotate and axially move the shaft, and a cam on the shaft to move the lever into and out of the path of the cam disk.

In testimony whereof I have signed my name.

FREDRIC EDHOLM.
